US00D460549S

(12) **United States Design Patent** (10) Patent No.: **US D460,549 S**
(45) Date of Patent: ** Jul. 16, 2002

(54) **COMBINATION CEILING FAN BLADES AND BLADE MOUNTING ASSEMBLY**

* cited by examiner

(75) Inventor: **Robert Sonneman**, Mamaroneck, NY (US)

Primary Examiner—Lisa Lichtenstein

(74) Attorney, Agent, or Firm—Jenkens & Gilchrist, P.C.

(73) Assignee: **Sonneman Design Group, Inc.**, Mamaroneck, NY (US)

(57) **CLAIM**

(**) Term: **14 Years**

The ornamental design for a combination ceiling fan blades and blade mounting assembly, as shown and described.

(21) Appl. No.: **29/151,480**

DESCRIPTION

(22) Filed: **Dec. 4, 2001**

FIG. 1 is a top view of the combination ceiling fan blades and blade mounting assembly in accordance with my design; FIG. 2 is a front elevation view of the combination ceiling fan blades and blade mounting assembly in accordance with my design;

(51) LOC (7) Cl. **23-04**

FIG. 3 is a bottom view of the combination ceiling fan blades and blade mounting assembly in accordance with my design; and,

(52) U.S. Cl. **D23/411**

FIG. 4 is a side elevation view of the combination ceiling fan blades and blade mounting assembly in accordance with my design.

(58) Field of Search D23/377, 379, D23/385, 411, 413; 416/5; D26/59, 71, 81-86

The front and rear elevational views are substantially identical except for the positioning of the blades.

(56) **References Cited**

The left and right side elevational views are substantially identical except for the positioning of the blades.

U.S. PATENT DOCUMENTS

The broken lines showing environmental structures are for illustrative purposes only and form no part of the claimed design.

D349,336 S * 8/1994 Tsuji D23/377
D425,610 S * 5/2000 Gee, II D23/377
D448,840 S * 10/2001 Gajewski D23/377
